POWDER PUFF AND METHOD FOR MANUFACTURING THE SAME

Roger Bihler, College Point, N. Y., assignor to
Baronet-Lorna Co., Inc., College Point, N. Y., a
corporation of New York

Original application July 8, 1932, Serial No.
621,343. Divided and this application January
30, 1933, Serial No. 654,170

6 Claims. (Cl. 132—78.5)

This invention relates to multi-ply enclosed turned articles, and more particularly to powder puffs and to a method for manufacturing the same.

5 In manufacturing powder puffs a plurality of plies of plush or velour fabric are superposed face to face or nap to nap and stitched for most of their periphery. Special machines have been devised to facilitate this stitching operation in order 10 to make possible quantity production methods, and such a machine is disclosed in my Patent No. 1,808,805 issued June 9, 1931. The pouch thus formed is inverted or turned inside out so as to bring the plush or velour surface outermost, during 15 or after which turning operation the puff may be stuffed with a suitable soft filling, if desired. The remaining opening has ordinarily invariably been stitched by hand, thereby greatly lengthening the time and increasing the cost of manufacture 20 of the powder puff.

The primary and general object of the present invention resides in the provision of a novel form of powder puff and of a method for so manufacturing the same that the powder puff will be 25 united entirely around its periphery by a single machine stitching operation performed in only a single sewing machine.

The present application is a division of my co-pending parent application Ser. No. 621,343 filed 30 July 8, 1932. The said parent application discloses the powder puff and method for making the same, and further discloses a novel powder puff sewing machine suitable for practicing the invention. The claims of the said parent application 35 are more particularly directed to the apparatus or sewing machine, while the claims of the present application are directed to the powder puff and method of making the same.

More particularly, one object of the present invention resides in the provision of a method of manufacturing a powder puff, in accordance with 40 which the puff is stitched entirely around its periphery until the last stitch comes immediately adjacent the first stitch, after which the loops of thread at the end stitches are quickly and readily opened to form a breach or opening through 45 which the puff may be turned. The ends of the thread may then be knotted by hand in order to close the temporarily open breach in the stitching. Still another object of the present invention 50 is to enlarge the breach obtained by opening the adjacent loops as aforesaid, and thereby to facilitate the turning operation; and with this object in view the first and last stitches are 55 elongated relative to the remaining or normal

stitches used around the periphery of the powder puff. This directly increases the available opening through which the puff is turned, and, at the same time, due to a loosening of the next remoter loops of stitching, the effective opening is still further increased.

Another object of the present invention resides in the production of an improved article or powder puff, the powder puff produced in accordance with the present method being characterized by 10 a smooth, soft, perfectly rounded or circular edge which is in no way marred either by hand stitching or by machine stitching of the character set forth in my copending application referred to. Still another object is to so close or 15 finish the peripheral stitching of the turned article that there will be no possibility of the stitching opening up or becoming loosened in course of use.

To the accomplishment of the foregoing and 20 such other objects as will hereinafter appear, my invention consists in the powder puff and method for making the same, as hereinafter are more particularly described in the specification and sought to be defined in the claims. The 25 specification is accompanied by a drawing in which:

Fig. 1 illustrates the embryo powder puff immediately after the stitching operation;

Fig. 2 is an edge view of the same with the 30 plies of fabric drawn slightly apart;

Fig. 3 shows the formation of a breach or opening in the powder puff after releasing the adjacent loops of stitching;

Fig. 4 illustrates how the puff may be turned, 35 and further how it may simultaneously be provided with a layer of filling or stuffing material;

Fig. 5 is an edge view of the powder puff after it has been turned and before the opening is 40 closed; and

Fig. 6 illustrates the method of closing the opening in and locking the stitching of the powder puff.

The method of my invention and the article produced thereby may best be explained by reference to Figs. 1 through 6 of the drawing. Referring to these figures, the multi-ply turned article is particularly exemplified by a powder puff, the said powder puff comprising plies of material 112 and 114 arranged in superposed relation and stitched entirely around their periphery by a line of machine stitching 116. In the case of a powder puff the fabric preferably is a soft piled material such as plush or velour, and the plies are arranged in face to face or nap to nap 50 55 55

relation, the piled surfaces subsequently being brought outermost by inverting or turning the embryo powder puff.

In accordance with the present invention, the line of stitching 116 is continued from an initial stitch 118 to a final stitch 120 which comes up quite close to the first stitch 118, thereby completely closing the pouch or embryo puff. This is in sharp contrast with the usual methods which leave a relatively large breach or gap in the stitching in order to permit the embryo puff to be turned. It should also be noted that the stitching is preferably performed with a pair of threads, an upper thread 122 and a lower thread 124, as is customary with ordinary machine stitching, and this pair of threads is carried entirely around the powder puff by the sewing machine until the stitching is terminated by the ends 126 and 128 of the upper and lower threads. The free ends of thread are preferably left substantial in length, as is indicated throughout the drawing, in order to readily permit a breach of substantial size to be formed between the plies of material 112 and 114, as is shown in Fig. 3, and to facilitate a manual tying operation, as is illustrated in Fig. 6.

If the edges of the plies of fabric are drawn apart slightly at the terminal of the stitching, an effect will be produced such as is illustrated in Fig. 2, exposing the loops 130 of the initial stitch 118 and the loops 132 of the final stitch 120. At the same time the next remote loops 134 and 136 may also become somewhat loosened.

With the aid of a needle, pin, or, more preferably, a specially designed hook such as the hook 138 shown in Fig. 3, the loops 130 and 132 may quickly and readily be opened, thereby producing the effect shown in Fig. 3. It should be understood that it is simply necessary to catch the hook 138 beneath the group of threads comprising the loops 130 and 132, and to thereupon draw the hook 138 upwardly, as a result of which the arrangement shown in Fig. 3, resulting in a substantial opening or breach 140, will be immediately and directly produced. This breach or opening 140 is then taken advantage of to permit the desired turning or inverting operation for the powder puff.

In order to enlarge the opening 140 and to thereby facilitate the turning operation, I have found it desirable to lengthen or increase the size of the first or last stitch or several stitches of the powder puff. This is clearly evident from an inspection of Fig. 1 in which it will be observed that the initial and terminal stitches 118 and 120 as well as the next remote stitches are substantially longer than the remaining or normal stitches 116. It is this change from the normal stitching operation which permits the breach or opening 140 to take the relatively large dimension shown in Fig. 3, even though the breach has been formed merely by loosening only the most closely adjacent loops 130 and 132 of the stitching.

The embryo puff is then turned through opening 140, and this turning operation may, if desired, be facilitated by the use of a clamp such as is shown in Fig. 4, the said clamp comprising an upright post 142 having an offset head 144 with which cooperates a reciprocable clamping jaw 146. By securing the edge of the material in the clamp at a point diametrically opposite the opening 140, it is then readily possible to draw the powder puff downwardly over the head 144 and about the post 142, the edge of one ply of material 112 being drawn downwardly at one side

of the post 142, while the edge of the other ply of material 114 is drawn downwardly at the opposite side of the post 142. If the powder puff is to be supplied with a filler or stuffing, this may most simply and conveniently be done by utilizing the same in the form of a lamination of filler material 148 preferably somewhat smaller in diameter than the outer plies 112 and 114, which lamination 148 may be placed on the outside of the puff before clamping the same, as is clearly shown in Fig. 4, so that upon turning the embryo puff as before described, the filler material 148 is brought inside of and spread uniformly throughout the turned puff.

Before passing on to the next stage of the process, it may not be amiss to point out that the women performing this turning operation become so skillful that ordinarily they do not need or desire to use clamping mechanism such as has been described, but instead simply employ a stick 15 or post which may, for example, be the post 142 provided with the offset head 144 but omitting the clamping jaw 146. The puff with or without the layer of filling material is then simply held against the head 144 with one finger, while the puff is turned downwardly over the post 142.

The turned powder puff then has an appearance somewhat as is illustrated in Fig. 5, the soft and delicate piled surface of the fabric being brought outermost, while the breach 140 is still left in its open condition. The loops 134 and 136 also remain in a relatively loose or slack state and this, it may be observed, is one of the things which helps make possible the turning of the powder puff, as shown in Fig. 4, because the slack in loops 35 134 and 136 effectively increases the size of the opening 140.

To close and finish the powder puff it is only necessary to tie the ends of the thread together. These ends may be tied in a number of ways, 40 either with a single knot or with a pair of knots, but I prefer to finish the puff by separately tying the end 122 to the end 124, and the end 126 to the end 128. When this procedure is followed it is easy to take up the slack in the end stitches and to 45 draw the threads taut, and at the same time the exposed edge of the puff may be finished in a smooth and soft manner by turning the loops or edges of the opening 140 inwardly during the knotting of the threads.

The operation is most conveniently though not necessarily performed by temporarily slipping the puff between a pair of clamping surfaces 150 and 152 so that both hands are left free for the tying operation. The clamp does not need to exert appreciable grip upon the powder puff, and in no way mars or injures the smooth and delicate pile surface of the same. While the puff is held in the clamp the operator simply ties the ends 122 and 124 together, as is illustrated in Fig. 6, after which 55 the ends 126 and 128 may be drawn taut and also tied together. The manner in which the ends of the thread pass through the outer or pile surface of the fabric, as is best shown in Fig. 5, insures that the edges of the opening 140 will turn inwardly when the threads are knotted together, but, if desired, the operator may take the precaution of urging the aforesaid edges inwardly during the tying operation.

The sewing operation is preferably performed 70 on a powder puff sewing machine which insures rapid and truly circular sewing, but the sewing machine is preferably modified to include automatic stitch lengthening mechanism arranged to elongate the first and last few stitches of the com- 75

plete sewing operation. A preferred form of sewing machine for this purpose is described and claimed in my copending parent application Ser. No. 621,343, previously referred to.

5 It is believed that my novel powder puff, which is machine stitched entirely around its periphery with only a single continuous pair of threads, and the method of making the same, as well as the many advantages thereof, will all be apparent 10 from the foregoing detailed description. The powder puff or, more generally, any turned enclosed article may be made with only a single machine operation, the material being stitched entirely around its periphery in either an ordinary 15 sewing machine or, more preferably, a specially designed machine modified for stitching, as heretofore described. The powder puff is completely machine stitched, and the usual hand stitching operation subsequent to the machine stitching of 20 the puff is entirely dispensed with. A few simple manual manipulations, as described in connection with Figs. 1 through 6, suffice to provide the desired inversion of the puff, simultaneous stuffing of the same, and closing the breach in the puff. 25 The breach is closed by threads which are nicely spaced to result in a smooth unmarred finish, and yet which are securely knotted to prevent opening of the puff at any future time. The method of my invention greatly speeds up and cheapens the 30 cost of manufacture of the powder puff, while the resulting article is far superior to that made by manual processes, both as regards regular configuration or outline (the complete line of stitching being truly circular), and also as regards 35 smoothness and softness of the pile at the edge of the powder puff.

It will be apparent that while I have shown and described my invention in preferred form, many changes and modifications may be made in the 40 method and structure disclosed without departing from the spirit of the invention, defined in the following claims.

I claim:

1. In the manufacture of enclosed turned multi-ply articles, the method which includes superimposing plies of material, machine stitching the plies of material from a starting point entirely around their peripheries back to approximately the starting point with a continuous line of substantially uniformly taut stitches, opening the loops of the adjacent end stitches and thereby providing an appreciable opening in the periphery of the article, turning the article through the aforesaid opening, and finally tying the original thread ends together in order to close said opening.
2. In the manufacture of powder puffs, the method which includes superimposing plies of material, machine stitching the plies of material from a starting point entirely around their peripheries back to approximately the starting point with a continuous line of substantially uniformly taut stitches with upper and lower threads, opening the inside loops of the upper and lower threads of the adjacent end stitches and thereby providing an appreciable opening in

the periphery of the stitched puff, with the four original thread ends projecting from the inner faces of the material, turning the puff through the aforesaid opening, and finally tying the ends of the threads together in order to close the aforesaid opening.

3. In the manufacture of powder puffs, the method which includes superimposing plies of material in inverted condition, machine stitching the plies of material entirely around their peripheries with upper and lower threads until the last stitch comes closely adjacent the first, the stitches being substantially uniformly taut, engaging the loops of the adjacent end stitches between the plies of material and lifting the same upwardly to open the loops and thereby provide an appreciable opening in the periphery of the stitched puff, turning the puff through the aforesaid opening and thereby bringing the four original ends of the threads to the outside of the puff, 20 and finally tying the ends of the threads together in order to turn in the edges of the opening and to close the said opening.

4. In the manufacture of powder puffs, the method which includes superimposing plies of material, machine stitching the same with two threads entirely around the periphery of the plies of material, elongating the first and last few stitches relative to the normal or remaining stitches, opening the loops of the adjacent end 25 and elongated stitches in order to provide a substantial opening, turning the puff through the aforesaid opening, and finally tying the ends of the upper and lower threads together in order to 30 close the opening.

5. In the manufacture of powder puffs, the method which includes superimposing plies of material, machine stitching the same entirely around the periphery of the plies of material back to approximately the starting point with a continuous line of substantially uniformly taut 40 stitches, opening the loops of the adjacent end stitches in order to provide a substantial opening, applying a layer of filler material to the exterior of the puff, thereafter turning the puff with 45 the filler material through the aforesaid opening, and finally tying the thread ends together in order to close the opening.

6. In the manufacture of powder puffs, the method which includes superimposing plies of material, machine stitching the same with two threads entirely around the periphery of the plies of material, elongating the first and last few stitches relative to the normal or remaining 50 stitches, opening the loops of the adjacent end and elongated stitches in order to provide a substantial opening, applying a layer of filler material to the exterior of the puff, thereafter turning the puff with the filler material through the aforesaid opening, and finally tying the upper 55 and lower threads at the starting end of the stitching together and also tying the upper and lower threads at the terminal end of the stitching together in order to close the opening.

65 ROGER BIHLER.
